UNITED STATES PATENT OFFICE.

JOHN P. WEIS, OF NYACK, NEW YORK, ASSIGNOR, BY MESNE ASSIGNMENTS, TO METROPOLITAN SEWING MACHINE CORPORATION, OF DOVER, DELAWARE, A CORPORATION OF DELAWARE.

SEWING-MACHINE.

1,277,005.

Specification of Letters Patent. Patented Aug. 27, 1918.

Application filed May 20, 1918. Serial No. 88,725.

To all whom it may concern:

Be it known that I, JOHN P. WEIS, a citizen of the United States, residing at Nyack, in the county of Rockland and State of New York, have invented certain new and useful Improvements in Sewing-Machines, of which the following is a specification.

This invention relates to sewing machines, and more particularly to improved means for supplying the work with an elastic strip, the object of the invention being to provide a mechanism which will hem the work, fold and attach a covering strip or tape to the raw edge of the hem and simultaneously 10 guide and tension an elastic band or strip into position to be stitched between the work and the covering strip, and to do this in a 15 very simple, efficient and rapid manner on a single machine of comparatively simple construction.

In the production of wearing apparel, such as shirt-waists, skirts, bloomers, etc., it is desirable to form a hem and to cover the raw edge of this hem with a folded tape or strip and at the same time insert an elastic strip so that when the hem is completed it will adjust itself to the wearer. To accomplish this object I have provided a two-needle sewing machine with means for forming a hem and for folding a strip, and also with a shiftable guiding means for the elastic or rubber band which is interposed between the two, together with a tensioning means for such elastic band and means for 20 operating it simultaneously with the shifting action of the elastic band guide by the action of the foot treadle or other suitable means.

In the drawings accompanying and forming part of this specification, Figure 1 is a top plan view of a part of a sewing machine, its cloth plate and throat plate, with the improvements referred to applied, thereto; Fig. 2 is a view of the improvement looking in the direction opposite to the direction of the arrow in Fig. 1; Fig. 3 is a view of the improvement looking in the direction of the arrow in Fig. 1; and Fig. 4 is a perspective view illustrating the work done by the machine.

Similar characters of reference indicate

corresponding parts in the different figures of the drawings.

The cloth plate 1 of a sewing machine has the throat plate 2 secured thereto, and which latter is provided with openings 3 for the feed dogs and the usual needle holes 4. This throat plate is cut away along the line 5 to receive the end 6 of a slide plate 7, and this slide plate is reduced as at 8 on each side to fit into a recess of the cloth plate and is provided with a retaining spring 9 to hold this slide plate securely in place. This spring is shown in two positions by dotted and full lines in Fig. 2. Secured to the slide plate by screws 10 is the shank 11 which supports the hem folder 12 which gives the work a half turn down and under; that is to say, the work extends down into the loop 13 so as to form the portion 14 (see Fig. 4), of the hem. This hem former is provided with an extension 15 overlying the cloth plate to facilitate the handling of the work. This former extends close up to the stitching position to guide the work in a uniform manner. The slide plate 7 is also recessed at 16 to receive a slide 17, which has secured thereto a flattened tube 18 for guiding the elastic or rubber band 19. This tube 18 operates in a recess 20 of the slide plate at right angles to the recess 16. The slide 17 has a wire or rod 21 secured thereto and bent at right angles and which has a beveled end 22 co-operating with a curved loop 23, (see Fig. 3), of the elastic tensioning means, comprising a member 24 which is pivotally attached, as at 25, to a plate 26 secured to an extending portion 27 of the slide plate 7. The tension member 24 is under the pressure of a spring 28, the pressure of which may be regulated by the nuts 29 carried by a post 30, (see Fig. 3). The plate 26 is provided with guiding ears 31 (see Fig. 3), for the elastic band. Attached to the bottom front edge of the slide plate 7 is an angle plate 32 provided with slots 33 to receive screws 34 and permit lateral adjustment and quick removal of a covering strip guiding means or guider shown in the form of a folder 35 supported by a bracket 36, carrying the screws 34. This strip folder is arranged to receive a strip at its

entrance end 37 and deliver the strip from the end 39 with both edges folded, and which strip is stitched in position to cover the raw edge of the hem and will therefore be designated as a covering strip.

It will be observed from the foregoing that the covering strip folder is located underneath the slide plate, that the elastic band guide or guider or guiding means operates in a recess in the top of the slide plate, and that the hem former or folder is practically flush with the top of the slide plate, so that a centralized delivery of the three parts to be stitched is obtained as they are fed to the stitching mechanism, and this greatly facilitates the handling of the work. The rubber band guide is shifted by means of a floor treadle 40, (see Fig. 3), connected by a chain 41 to a lever 42 which rocks a shaft 43 supported in bearings 44 carried by the cloth plate 1. A coiled spring 45 has one end secured to one of the bearings 44 and its other end secured to a collar 46 provided with a stop screw 47, which serves to return the parts to their initial position after operation by the treadle. A similar collar 48 limits endwise movement of the shaft 43 in its bearings. A crank 49 carried by the shaft 43 operates a link 50 connected, as at 51, with the slide 17. This connection 51 is in the form of a hook for quick removal and replacement of the attachments for the purpose of threading or caring for the machine.

15 In the operation of the machine a strip 55 is introduced into the bottom folder 35, an elastic strip or band interposed between the tensioning members 24 and 26 and passed through the tube 18, while the goods is placed in the hem folder 13. When the treadle 40 is depressed the rubber band 19 is shifted to one side so that it is stitched along its edge, as at 52, (see Fig. 4), to the goods and the folded strip 55. At this time 45 the tension opener 22 is in position to relieve the tension on the elastic strip. After a suitable portion of the work has passed the stitching mechanism the treadle 40 is released, whereupon the rubber band guiding mechanism is shifted into its normal position so as to guide the rubber band free from the needles, and at which time the tension opener 22 is in the position shown in Fig. 3 and permits the tensioning members 24 and 26 to close and grip the rubber band so that its feeding movement is retarded or prevented sufficiently, so that the elastic strip is placed under great tension and stretched to a great extent, while the stitching proceeds free of the elastic strip say from the points 53 to 54. At this time the treadle is again depressed to shift the rubber guide so that the stitches pass through the rubber, as at 55. The tensioning members are then opened and the rubber is fed

under normal conditions free from stretch, leaving that portion of the garment free from gathers or ruffles. In other words, when the garment is removed from the machine that portion of the elastic strip which has been stretched and has not been stitched returns to its normal condition and so gathers the hem in the manner shown between the points 53—54, Fig. 4.

I claim as my invention:

1. In a sewing machine, the combination of means for folding a hem in the work, means for folding and guiding a covering strip into position to cover the raw edge of the hem, means for guiding an elastic strip into position to be stitched between the work and the covering strip, and means for shifting said elastic strip toward and from the stitch line and simultaneously placing the strip under tension when in one of its shifted positions.

2. In a sewing machine, the combination of means for folding a hem in the work, means for folding and guiding a covering strip into position to cover the raw edge of the hem, means for guiding an elastic strip into position to be stitched between the work and the covering strip, and means for shifting said elastic strip toward and from the stitch line and simultaneously placing the strip under tension when shifted away from the stitch line.

3. In a sewing machine, the combination of means for folding a hem in the work, means for folding both edges of and guiding a covering strip into position to cover the raw edge of the hem, means for guiding an elastic strip into position to be stitched between the work and the covering strip, and means for shifting said elastic strip toward and from the stitch line and simultaneously placing the strip under tension when in one of its shifted positions.

4. In a sewing machine, the combination of means for folding a hem in the work, means for folding both edges of and guiding a covering strip into position to cover the raw edge of the hem, means for guiding an elastic strip into position to be stitched between the work and the covering strip, and means for shifting said elastic strip toward and from the stitch line and simultaneously placing the strip under tension when shifted away from the stitch line.

5. In a sewing machine, the combination of means for folding a hem in the work, means for guiding a covering strip into position to cover the raw edge of the hem, means for guiding an elastic strip into position to be stitched between the work and the covering strip, and means for shifting said elastic strip toward and from the stitch line and simultaneously placing the strip under tension when in one of its shifted positions.

6. In a sewing machine, the combination of means for forming a hem in the work, means for guiding a covering strip into position to cover the raw edge of the hem, means for guiding an elastic strip into position to be stitched between the work and the covering strip, means for shifting said elastic strip to and from the stitch line, and means for clamping said elastic strip in one of its positions and for releasing it when shifted into the other of its positions. 70
7. In a sewing machine, the combination of means for forming a hem in the work, means for guiding a covering strip into position to cover the raw edge of the hem, means for guiding an elastic strip into position to be stitched between the work and the covering strip, means for shifting said elastic strip to and from the stitch line, and means for clamping said elastic strip when shifted away from the stitch line and for releasing it when shifted into position to be stitched. 80
8. In a sewing machine, the combination of means for forming a hem in the work, means for guiding a covering strip into position to cover the raw edge of the hem, means for guiding an elastic strip into position to be stitched between the work and the covering strip, means for shifting said elastic strip to and from the stitch line, and means for placing the elastic strip under tension when shifted into one of its positions and for releasing such tension when shifted into the other of its positions. 85
9. In a sewing machine, the combination of hemming means, a covering-strip-guiding means, an elastic-strip-guiding means, means for shifting said last guiding means thereby to shift the elastic strip into and out of the stitch line, and means for placing the elastic strip under tension at one time and for releasing such tension at another time. 95
10. In a sewing machine, the combination of means for guiding a strip into position to be stitched, means for shifting said strip to and from the stitching position, means for placing said strip under tension when shifted into one of said positions and for releasing it when shifted into the other of said positions, and means for supplying a covering strip. 105
11. In a sewing machine, the combination of means for guiding a strip into position to be stitched, means for shifting said strip to and from the stitching position, means for placing said strip under tension when shifted into one of said positions and for releasing it when shifted into the other of said positions, means for supplying a covering strip, and means for forming a hem between which and the covering strip the elastic strip is fed. 115
12. In a sewing machine, the combination of means for guiding an elastic strip to the stitching mechanism, means for clamping the strip at one time and releasing it at another time, means for shifting the strip into and out of the path of the stitching mechanism, and means for forming a hem and for guiding a covering strip to cover the raw edge of the hem. 120
13. In a sewing machine, the combination of means for guiding an elastic strip to the stitching mechanism, means for holding said strip in the path of the stitching mechanism at one time and out of the path thereof at another time and for placing the strip under tension during one of those times and for releasing the tension thereon during another of those times, and means for guiding a covering strip simultaneously with the guiding of the elastic strip to the stitching mechanism. 125
14. In a sewing machine, the combination of means for guiding an elastic strip to the stitching mechanism, means for holding said strip out of the path of the stitching mechanism while placing it under tension and for shifting said strip into the path of the stitching mechanism and releasing the tension thereon, and means for guiding a covering strip to the stitching mechanism. 130
15. In a sewing machine, the combination of means for guiding an elastic strip to the stitching mechanism, means for holding said strip out of the path of the stitching mechanism while placing it under tension and for shifting said strip into the path of the stitching mechanism and releasing the tension thereon, means for guiding a covering strip to the stitching mechanism, and means for hemming the work simultaneously with the guiding of the elastic strip and the guiding of the covering strip. 135
16. In a sewing machine, an elastic-strip-guiding means comprising a shiftable strip guide, a slide carrying the same, a rock shaft connected with the slide, means for operating said rock shaft, clamping means for the strip, and means connected with said slide for releasing said clamping means. 140
17. In a sewing machine, an elastic-strip-guiding means comprising a shiftable strip guide, a slide carrying the same, a rock shaft connected with the slide, means for operating said rock shaft, clamping means for the strip, and means connected with said slide for releasing said clamping means and comprising a bevel-ended member. 145
18. In a sewing machine, an elastic-strip guiding means comprising a shiftable strip guide, a slide carrying the same, a rock shaft connected with the slide, means for operating said rock shaft, clamping means for the strip, means connected with said slide for releasing said clamping means, and a folder for folding a covering tape. 150
19. In a sewing machine, an elastic-strip 155

- guiding means comprising a shiftable strip guide, a slide carrying the same, a rock shaft connected with the slide, means for operating said rock shaft, clamping means for the strip, means connected with said slide for releasing said clamping means, a folder for folding a covering tape, and a hemmer for forming a hem.
20. In a sewing machine, an elastic-strip guiding means comprising a shiftable strip guide, a slide carrying the same, a rock shaft connected with the slide, means for operating said rock shaft, clamping means for the strip, means connected with said slide for releasing said clamping means, a folder for folding a covering tape, and a hemmer for forming a hem, said elastic-strip guide being located above the folder and below the hemmer.
20. 21. In a sewing machine, the combination of means for forming a hem, means for folding a covering strip, means for guiding a strip into position to be stitched, said strip guiding means being located between the hem forming means and the strip folding means and below the hem forming means, and means operative at the will of the operator without stopping the stitching mechanism for shifting one of said means laterally relatively to the other two means.
22. In a sewing machine, the combination of means for forming a hem, means for folding a covering strip, means for guiding a strip into position to be stitched, said strip guiding means being located between the hem-forming means and the strip-folding means and the latter below the hem-forming means; and means for shifting said strip guiding means toward and from the stitch line.
23. In a sewing machine, the combination of means for forming a hem, means for folding a covering strip, means for guiding an elastic strip into position to be stitched, said elastic-strip guiding means being located between the hem-forming means and the strip-folding means, means for shifting said elastic-strip guiding means toward and from the stitch line, and means for placing the strip under tension at one time and for releasing the tension at another time.
24. In a sewing machine, the combination of means for forming a hem, means for folding a covering strip, means for guiding an elastic strip into position to be stitched, said elastic-strip guiding means being located between the hem-forming means and the strip-folding means, means for shifting said elastic-strip guiding means toward and from the stitch line and comprising a slide and a rock shaft, and means for operating them.
25. In a sewing machine, the combination of means for forming a hem, means for folding a covering strip, means for guiding an elastic strip into position to be stitched, said
- elastic-strip guiding means being located between the hem-forming means and the strip-folding means, means for shifting said elastic-strip guiding means toward and from the stitch line and comprising a slide and a 70 spring-actuated rock shaft, and means for operating said rock shaft.
26. In a sewing machine, the combination of means for forming a hem, means for folding a covering strip, means for guiding an elastic strip into position to be stitched, said elastic-strip guiding means being located between the hem-forming means and the strip-folding means, means for shifting said elastic-strip guiding means toward and from the stitch line, means for placing the strip under tension at one time and for releasing the tension at another time and comprising a slide and means for operating it.
27. In a sewing machine, the combination of a sliding member, an elastic strip guide carried thereby for movement therewith, means for shifting said slide and thereby the strip guide toward and from the stitch line, clamping means in position to cooperate with the strip, and means carried by the slide for releasing said clamping means at a predetermined time.
28. In a sewing machine, the combination of a sliding member, an elastic strip guide carried thereby for movement therewith, means for shifting said slide and thereby the strip guide toward and from the stitch line, clamping means in position to cooperate with the strip, and means carried by the slide for releasing said clamping means at a predetermined time; said slide-operating means comprising a rock shaft and a treadle connected therewith for actuating it.
29. In a sewing machine, the combination of a sliding member, an elastic strip guide carried thereby for movement therewith, means for shifting said slide and thereby the strip guide toward and from the stitch line, clamping means in position to cooperate with the strip, and means carried by the slide for releasing said clamping means at a predetermined time, a hem former located above said elastic-strip guide, and a strip-folding guide located below said elastic-strip guide.
30. In a sewing machine having a cloth plate, the combination of a slide plate supported thereby, and an elastic-strip guiding and shifting means carried thereby and means for placing the strip under tension at one time.
31. In a sewing machine having a cloth plate, the combination of a slide plate supported thereby, an elastic-strip guiding and shifting means carried thereby, and means for placing said elastic strip under tension at a predetermined time also carried by said slide plate.
32. In a sewing machine having a cloth plate, the combination of a slide plate car-

- ried thereby, means for forming a hem carried by said slide plate, and means for guiding a strip to the stitching mechanism and also carried by said slide plate.
33. In a sewing machine having a cloth plate, the combination of a slide plate carried thereby, means for forming a hem carried by said slide plate, means for guiding a strip to the stitching mechanism and also carried by said slide plate, and means for folding and guiding a covering strip also carried by said slide plate.
34. In a sewing machine having a cloth plate, the combination of a slide plate carried thereby, means for forming a hem carried by said slide plate, means for guiding an elastic strip to the stitching mechanism and also carried by said slide plate, means for folding and guiding a covering strip also carried by said slide plate, and means for placing the elastic strip under tension and also carried by said slide plate.
35. In a sewing machine having a cloth plate, the combination of a slide plate carried thereby, means for forming a hem carried by said slide plate, means for guiding an elastic strip to the stitching mechanism and also carried by said slide plate, means for folding and guiding a covering strip also carried by said slide plate, and means for shifting said elastic-strip guide and supported by said slide and cloth plate.
36. In a sewing machine, the combination of means for forming a hem, means for guiding a covering strip, means for guiding an elastic strip into position to be stitched, said elastic strip guiding means being located between the hem forming means and the covering strip guiding means and below the hem forming means, and means for placing the elastic strip under tension at one time and for releasing the tension at another time.
37. In a sewing machine having a cloth plate, the combination of a slide plate carried thereby, means for forming a hem carried by said slide plate, means for guiding an elastic strip to the stitching mechanism and also carried by said slide plate and means for placing the elastic strip under tension at one time.
38. In a sewing machine having a cloth plate, the combination of a slide plate carried thereby, means for forming a hem carried by said slide plate, and means for guiding a strip to the stitching mechanism and also carried by said slide plate, the latter located below the hem forming means.
39. In a sewing machine having a cloth plate, the combination of a slide plate carried thereby, means for guiding a strip to the stitching mechanism and carried by the slide plate, and means also carried by said slide plate below the strip guiding means for guiding a covering strip.
40. In a sewing machine having a cloth plate, the combination of a slide plate carried thereby, means for forming a hem carried by said slide plate, and means for guiding a strip to the stitching mechanism and also carried by said slide plate, the latter located below the hem forming means, and means also carried by said slide plate below the strip guiding means for guiding a covering strip.
41. In a sewing machine having a cloth plate, the combination of means for forming a hem, means for guiding a covering strip, and means for guiding another strip into position to be stitched, said last strip guiding means being located between the hem forming means and the first strip guiding means and all of said means being supported by the cloth plate, and means operative at the will of the operator without stopping the stitching mechanism for shifting one of said means laterally relatively to the other two means.
42. In a sewing machine having a recessed cloth plate, a hem folder, a strip guider, and a covering strip guider, all secured to means located within the recess of said cloth plate.
43. In a sewing machine, a hem folding device, a strip guiding device, and a covering strip guiding device, all secured in position below the top ply of material to be stitched, and means operative at the will of the operator, without stopping the stitching mechanism, for shifting one of said devices laterally with respect to the other two devices.
44. In a sewing machine, a hem folder, a strip guider and a covering strip guider all secured in position below the top ply of material to be stitched, and means for shifting the first strip guider.
45. In a sewing machine, a hem folder, a strip guider and a covering strip guider all secured in position below the top ply of material to be stitched, and means for shifting the first strip guider and placing it under tension at one time.
46. In a sewing machine having a recessed cloth plate, a hem folder, a strip guider, and a covering strip guider, all secured to means located within the recess of said cloth plate, the first strip guider being located between the hem folder and covering strip guider with the hem folder above the strip guider.
47. In a sewing machine having a recessed cloth plate, a hem folder, an elastic strip guider, and a covering strip guider, all secured to means located within the recess of said cloth plate, the elastic strip guider being located between the hem folder and covering strip guider with the hem folder above the elastic strip guider, and means for placing the strip under tension at one time.

48. In a sewing machine having a recessed cloth plate, a hem folder, a strip guider, and a covering strip guider, all secured to means located within the recess of said cloth plate, 5 the first strip guider being located between the hem folder and covering strip guider with the hem folder above the first strip guider, and means for shifting the strip guider.
- 10 49. In a sewing machine, having a recessed cloth plate, a hem folder, an elastic strip guider, and a covering strip guider, all secured to means located within the recess of said cloth plate, the elastic strip guider 15 being located between the hem folder and covering strip guider with the hem folder above the elastic strip guider, and means for shifting the elastic strip guider and placing it under tension at one time.
- 20 50. In a sewing machine having a cloth plate, the combination of a slide plate carried thereby and having a recess therein, means for forming or folding a hem located substantially flush with the top of said slide plate, 25 means for guiding a strip to the stitching mechanism and located in the recess of said slide plate, and means for guiding a covering strip and located below the top of said slide plate.
- 30 51. In a sewing machine having a cloth plate, the combination of a slide plate carried thereby, a hem folder or former, a strip guider and a covering strip folder or guider, one of said parts carried below the slide plate, another substantially flush with the top of said plate, and another between the other two.
- 35 52. In a sewing machine having a cloth plate, the combination of a hem folder or former, a strip guider, and a covering strip folder or guider, one located at the top of the cloth plate, another under the same, and the other between the two.
- 40 53. In a sewing machine having a cloth plate, the combination of a hem folder or former, a strip guider and a covering strip folder or guider, one located at the top of the cloth plate, another under the same, and the other between the two, and means for 45 shifting the first strip guider to one side of its normal position.
- 45 54. In a sewing machine, the combination of feeding mechanism, stitch forming mechanism having a needle, means for guiding a fabric to the stitch forming mechanism and hemming the same, a covering strip guiding means, a guide for directing an elastic tape in the path of the needle, whereby it is stitched to the fabric, and manually controlled means for placing the elastic tape under tension and releasing such tension at the will of the operator without stopping the stitching mechanism.
- 50 55. In a sewing machine, the combination 55 of a feeding mechanism, stitch forming mechanism having a plurality of needles, means for guiding a fabric to the stitching mechanism and hemming the same, a covering strip guiding means, a guide for directing the elastic tape in the path of the needle, means for placing a predetermined tension on the elastic tape at a point in front of the needle, and manually controlled means for releasing the tension at the will of the operator without stopping the stitching mechanism.
- 55 56. In a sewing machine, the combination of feeding mechanism, stitch forming mechanism having a plurality of needles, means for guiding a fabric to the stitching mechanism and hemming the same, a covering strip guiding means, an elastic tape guide for directing the tape into the path of said needles, a tension shoe for engaging the tape in front of the needles, a spring for pressing said shoe against the tape at a predetermined pressure, and manually controlled means for raising the tension of the shoe from the tape at the will of the operator without stopping the stitching mechanism.
- 60 57. In a sewing machine, the combination of feeding mechanism, stitch forming mechanism having a plurality of needles, means for guiding a fabric to the stitching mechanism and hemming the same, a covering strip guiding means, a guide for directing an elastic tape into the path of the needles, a tension shoe adapted to engage said elastic tape in said tape guide and retard the free movement of the elastic tape, whereby the feed of the machine stretches the tape as it is presented to the needles, a spring for normally pressing said tension shoe against the tape, manually controlled means for lifting the tension shoe from the tape and permitting the free feed of the tape to the needles without stopping the stitching mechanism.
- 65 58. In a sewing machine, the combination of feeding mechanism, stitch forming mechanism having a plurality of needles, means for guiding a fabric to the stitching mechanism and hemming the same, a covering strip guiding means, a guide for directing an elastic tape into the path of the needles, a tension shoe adapted to engage said elastic tape in said tape guide and retard the free movement of the elastic tape, whereby the feed of the machine stretches the tape as it is presented to the needles, a spring bar carrying said tension, means for engaging the said bar for varying the tension of the shoe against said elastic tape, and manually controlled means for engaging said bar to raise the shoe to release the tension on the elastic tape without stopping the stitching mechanism.
- 70 59. In a combined folder and guide for sewing machines, the combination of a stationary scroll-guide, a stationary band-guide, an adjustably secured tape-guide and

means for effecting said adjustment including a rock shaft and a manually controlled shifting link connected with said rock shaft and pivotally connected at one end with 5 said tape-guide to give to the latter movements in directions transverse to the lines of seam formation.

60. In a combined folder and guide for sewing machines, the combination of a stationary scroll-guide, a stationary band-guide, an adjustably secured tape-guide, an adjustable tape-tensioning spring, and means for effecting the adjustment of said tape guide and including a manually controlled shifting link pivotally connected at one end with said tape-guide to give to the latter movements in directions transverse to the lines of seam formation.

61. In a combined folder and guide for 20 sewing machines, the combination of a stationary scroll-guide, a stationary band-guide, an adjustably secured tape-guide, an adjustable tape-tensioning spring adjustable independently of said tape-guide to 25 regulate its tension on the tape, and means

for effecting the adjustment of said tape guide and including a manually controlled shifting link pivotally connected at one end with said tape-guide to give to the latter movements in directions transverse to the 80 lines of seam formation and means including a tape releasing element brought into effective operation on the lateral movements of said tape-guide.

62. In a combined folder and guide for 25 sewing machines, the combination of a stationary scroll-guide, a stationary band-guide, an adjustably secured tape-guide whose delivery is provided with spaced walls, and means for effecting the adjustment of said tape guide and including a manually controlled shifting link pivotally connected at one end with said tape-guide to give to the latter movements in directions 40 transverse to the lines of seam formation.

Signed at Nyack, in the county of Rockland and State of New York, this 13th day of May, 1916.

JOHN P. WEIS.
